UNITED STATES PATENT OFFICE.

WILLIAM MAXWELL, OF PITTSBURG, PENNSYLVANIA.

METALLIC POLE.

SPECIFICATION forming part of Letters Patent No. 726,801, dated April 28, 1903.

Application filed December 20, 1902. Serial No. 135,977. (No model.)

To all whom it may concern:

Be it known that I, WILLIAM MAXWELL, a citizen of the United States of America, residing at Pittsburg, in the county of Allegheny and State of Pennsylvania, have invented certain new and useful Improvements in Metallic Poles, of which the following is a specification.

This invention relates to girders and columns, and particularly to that class known as "metallic" poles.

The object of the invention is to produce a pole-casing and internal braces, formed integral with the casing, which may be produced at a single operation and thereafter shaped to form the pole and braces in certain relation.

Furthermore, the object of the invention is to produce a metallic pole having internal braces of variously-modified form, all of which are within the scope of the invention, in that they are formed integral with the casings.

A further object of the invention is to produce a metallic pole which by reason of the structural features will prove efficient and satisfactory in use, strong and durable, and comparatively inexpensive of manufacture.

With the foregoing and other objects in view the invention consists in the details of construction and in the arrangement and combination of parts, to be hereinafter more fully set forth and claimed.

In describing the invention in detail reference will be had to the accompanying drawings, forming part of this specification, where-in like characters denote corresponding parts in the several views, and in which—

Figure 1 is a view in elevation of a metallic pole, broken away to show the interior. Fig. 2 is a plan view with the top removed. Figs. 3, 4, 5, and 6 are similar views embodying modifications.

In the drawings, 7 indicates a shell or casing in which the braces 8 and 9 are formed integral, the said braces extending inwardly and parallel to the center, as at A, and then bent in diametrically opposite deviations to contact with the inner surface of the casing. The brace 8 has its edge contacting with the casing, while the leg forming the brace 9 is of sufficient length to be bent on itself and

extend slightly past the center, then bent at right angles to the braces 8 and 9 and forming a brace 10, terminating in contact with the inner surface, approximately opposite the joint of the casing. Bands 11 are secured on the outer surface of the casing by shrinking or by frictional engagement, such bands being provided in connection with the modifications, as hereinafter described.

In the form shown in Fig. 3 the braces 12, 13, and 14 are bent to form a triangular frame which contacts with the inner surface of the casing at the points 15 and 16, the brace 13 having its end bent at an angle at 17 to form a foot-like portion bearing on the brace 14.

In the modification shown in Fig. 4 the braces 18, 19, 20, and 21 are formed by bending the integral portion of the casing to form a square frame, the edge 22 and 23 terminating in contact with the inner surface of the casing and with the angular portions of the braces also contacting with the inner surface. This form will prove more rigid than that shown in Fig. 3, though for poles of comparatively large diameters the modification in Fig. 3 would be preferable.

The form shown in Fig. 5 is similar to that of Fig. 4, except that the braces 24, 25, 26, and 27 are bent back on themselves and extend parallel a short distance, this being provided for the purpose of increasing or diminishing the size of the frame formed by the braces, the same being adjustable to fit interior diameters varying somewhat.

In Fig. 6 the casing B is elliptical, and the braces 28 and 29 lie parallel across the inner axis and engage the inner surface of the casing to prevent collapse. The strength of the casing in the direction of the major axis being greater than that in the direction of the minor axis a brace in that direction will be found unnecessary for ordinary use.

Having fully described my invention, what I claim as new, and desire to secure by Letters Patent, is—

1. In a metallic pole, a casing and braces integral therewith extending within the casing and bent to engage the inner surface of the casing.
2. In a metallic pole, a casing and braces

integral therewith extending within the casing, said braces being bent to engage the casing at varying points.

3. In a metallic pole an elliptical casing and
5 braces integral therewith extending within
the casing across the minor axis and engaging
the inner surface of the casing.

In testimony whereof I affix my signature,
in the presence of two witnesses, this 19th day
of December, 1902.

WILLIAM MAXWELL.
